(57) **CLAIM**

The ornamental design for an LED lamp, as shown and described.

DESCRIPTION

FIG. 1 is a perspective view of the ornamental design for a LED lamp;

FIG. 2 is a side elevational view thereof, the other sides being similar;

FIG. 3 is a top view thereof; and,

FIG. 4 is a bottom view thereof.

The broken lines illustrating portions of the LED lamp show environmental features only, and form no part of the claimed design.
